UNITED STATES PATENT OFFICE.

WILLIAM M. GRIFFITH, OF BALTIMORE, MARYLAND, ASSIGNOR TO THE
GRIFFITH MANUFACTURING COMPANY, OF SAME PLACE.

DESIGN FOR A NECKTIE.

SPECIFICATION forming part of Design No. 21,977, dated November 8, 1892.

Application filed October 10, 1892. Serial No. 448,457. Term of patent 3½ years.

To all whom it may concern:

Be it known that I, WILLIAM M. GRIFFITH, a citizen of the United States, residing at Baltimore city, in the State of Maryland, have 5 invented a certain new and improved Design for Neckties, of which the following is a specification.

My design has relation to a new shape for neckties.

10 As illustrated in the accompanying drawing, it comprises a narrow strip A, fish-tail-shaped ends b, and substantially diamond or lozenge shaped parts b' between the fish-tail

ends and the narrow strip proper, thus forming a contracted part a between the fish-tail 15 ends and the diamond-shaped parts.

What I claim is—

The design for a necktie, substantially as shown and described.

In testimony whereof I affix my signature in 20 the presence of two witnesses.

WILLIAM M. GRIFFITH.

Witnesses:

JNO. T. MADDOX,
T. PARKER DAVIS.
